US0D1075586S

(12) **United States Design Patent** (10) **Patent No.:** **US D1,075,586 S**
(45) **Date of Patent:** **** May 20, 2025**

(54) **MODEL VEHICLE LIGHTED BUMPER ASSEMBLY**

(71) Applicant: **TRAXXAS, L.P.**, McKinney, TX (US)

(72) Inventors: **Trent Collins**, McKinney, TX (US);
Otto Karl Allmendinger, Rowlett, TX (US); **Adam Cole Ewing**, McKinney, TX (US); **Kent Poteet**, Lucas, TX (US)

(73) Assignee: **TRAXXAS, L.P.**, McKinney, TX (US)

(**) Term: **15 Years**

(21) Appl. No.: **29/829,466**

(22) Filed: **Mar. 4, 2022**

(51) **LOC (15) Cl.** **26-06**

(52) **U.S. Cl.**

(57) **CLAIM**

The ornamental design for a model vehicle lighted bumper assembly as shown and described.

DESCRIPTION

FIG. 1 is an upper, right, front perspective view of a model vehicle lighted bumper assembly showing our new design; FIG. 2 is a front elevation view thereof; FIG. 3 is a rear elevation view thereof; FIG. 4 is a right side elevation view thereof; FIG. 5 is a left side elevation view thereof; FIG. 6 is an upper plan view thereof; FIG. 7 is a lower plan view thereof; FIG. 8 is an upper, left, rear perspective view thereof; and, FIG. 9 is a lower, right, front view of the model vehicle lighted bumper assembly.

In the drawings, the broken lines illustrate portions of the model vehicle lighted bumper assembly that form no part of the claimed design.

1 Claim, 6 Drawing Sheets
